UNITED STATES PATENT OFFICE.

GEORGE C. TAFT, OF WORCESTER, MASSACHUSETTS, ASSIGNOR TO
THOMAS H. DODGE, OF NASHUA, NEW HAMPSHIRE.

IMPROVED SCREW-WRENCH.

Specification forming part of Letters Patent No. 41,747, dated February 23, 1864.

To all whom it may concern:

Be it known that I, GEORGE C. TAFT, of the city and county of Worcester, and State of Massachusetts, have invented a certain new and useful Improvement in Screw-Wrenches; and I do hereby declare that the following is a full, clear, and exact description of the same, reference being had to the accompanying drawings, forming a part of this specification, and in which—

Figure 1 represents a side view of my improved wrench, and Fig. 2 represents a longitudinal section thereof.

In the drawings, A represents the stationary jaw; B, the shank upon which the movable jaw, C slides when operated upon by the male screw D.

E is the ferrule in which the rear end, a, of the male screw D rests.

F is the rosette grooved out and fitted to work into the parallel grooves b b in the shank B, whereby all strain upon the ferrule E is transferred to the shank B, when the wrench is used in the ordinary manner.

The rear sides of the grooves b b are perpendicular, while their frontsides are inclined, all as fully shown in the drawings, and particularly Fig. 2.

The projections c c of the rosette F are also formed with perpendicular rear sides, and inclined or beveled front sides. In a previous invention, for which I have applied for Letters Patent, the sides of the grooves were perpen-

dicular, both in front as well as in the rear, the object of the grooves being to relieve the ferrule of the back strain from the rosette. It is important that the rear sides should be perpendicular, since the strain in holding the jaw C to its work comes upon two such surfaces.

The front sides have to bear considerable strain and abrasion in pounding, or when the wrench is used as a hammer, since the motion and force of blow both tend to throw the movable jaw C forward, and with inclined or beveled surfaces, as shown in the drawings, there is less liability of the edges heading up, &c., than with the perpendicular sides, besides the projections b b and d are, for a given amount of metal, stronger and more effective than they would be with perpendicular sides in front as well as in the rear.

Having described my improved wrench, what I claim as of my invention, and desire to secure by Letters Patent, is—

The combination, in a wrench in which the strain is transferred from the ferrule to the shank, as described, of one or more grooves, b, with perpendicular rear and beveled or inclined front side or sides, with one or more projections, c, of corresponding form, on the rosette F, substantially as and for the purposes set forth.

GEO. C. TAFT.
